SPRAY GUN

Walter R. Sheeter, La Habra, Calif., assignor to All-Power Manufacturing Co., Montebello, Calif., a corporation of California

Filed Mar. 25, 1968, Ser. No. 11,109

Term of patent 14 years

U.S. Cl. 23—17
Int. Cl. D23—01

FIG. 1 is a side elevational view of a spray gun embodying my new invention;
FIG. 2 is an enlarged side elevational view thereof;
FIG. 3 is a top plan view thereof;
FIG. 4 is a bottom plan view thereof;
FIG. 5 is a rear view thereof; and
FIG. 6 is a front view thereof.

The dominant features of my design reside in the portions shown in full lines, it being understood that the fragmentary broken line showing of an air supply line in FIG. 1 is for purposes of illustration only. The broken line showing of the nozzle has been omitted from FIGS. 2 through 6 for convenience of illustration only.

I claim:
The ornamental design for a spray gun, as shown and described.
